CRIMPING TOOL

Ralph G. Arey, Brockton, Mass., assignor to Ward
Machine Company, Inc., Brockton, Mass., a
corporation of Massachusetts

Application October 21, 1949, Serial No. 122,801

1 Claim. (Cl. 81—15)

1 My present invention is a novel and improved crimping tool, preferably designed as a portable hand device although capable of being power-actuated and in any size desired.

It is an important object of my present invention to provide a light, strong, inexpensive, quick-operating, and powerful hand crimping tool which can be utilized by a housewife in crimping and sealing the tops or lids of containers, such for example as the metal containers now in general use for enclosing articles of food in deep-freeze refrigerators. These containers are usually made of very thin aluminum of rectangular box-form, and with a flanged lid fitting on the top to close the container. It is desirable to have such a lid sealed or otherwise attached to the walls and ends of the container to thus provide a closed receptacle to protect the contents.

Heretofore, it has required a slow and difficult hand-rolling or other tool to effect such a closing operation.

My present crimping device is capable of effecting a crimping, uniting, and closing operation, firmly joining the cover to the lower portion of the container on both sides and ends, although these are of different lengths; and, furthermore, my improved crimper is directed and arranged to provide ample power for the metal-closing action required and yet with a minimum of manual strength.

In carrying out my invention, I provide a tool with a pair of jaws pivoted together in a special manner to effect a combined forcing of the lid and box portions into a sealed contact with ample capacity and power to unite the depending flange of the lid and the adjacent edge portions of the box into an almost air-tight union by a slight squeezing action of the handles of the device.

Ample leeway is provided to engage material of variable thickness as well as of different lengths so that either a square or rectangular box can have the sides and ends effectively united by the same crimping tool.

Referring to the drawings illustrating a preferred embodiment of my invention:

Fig. 1 is a plan view of my crimping tool shown in upside-down position;

Fig. 2 is a side view;

Fig. 3 is a longitudinal cross-sectional view;

Fig. 4 is a front end view;

Fig. 5 is a view in perspective of a container with the cover applied ready for the operation of my hand-crimping tool;

Fig. 6 is an enlarged cross-sectional view partly broken away showing the crimping action and

2 detailed construction of the pivot and box and cover-engaging portions;

Fig. 7 is a fragmentary plan view after the crimping action; and

Fig. 8 is a fragmentary side elevational view of the crimped edge of the lid or cover and box.

As shown in the drawings, my crimping tool comprises a pair of handle-like members to be grasped by the hand of the user, each handle extending into a cross-head portion which is united on a floating pivot. The top handle is designated at 1 with a cross-head portion indicated at 2, the handle preferably being stamped out with a channel-like member with depending sides 3—3 and an extension 4 on the sides of the cross-head portion, see Figs. 2 and 3. The lower part of the cross-head 2 is preferably formed with a plurality of teeth 7, the opposite side walls of the portion 4 being the extension of the flanges 3—3 already formed in the head 2. I provide a pair of slots 8—8 which have a cam conformation as indicated at 9. These are formed to receive the pivot pin 20 in the lower handle 10, which latter is also formed with a channel member with side walls 12—12 extending into the cross-head 15, which latter is of slightly less length than the width in the cross-head 2, and the lower handle 10 and its side flanges 12—12 are of slightly less width than that of the top or upper handle 1 so that the two handles may be interlocked as they are squeezed toward each other on the pivot 20.

Preferably I form the pivot 20 as short studs each wedged or secured in opposite ends of the cross-head 15 of the lower member and projecting sufficiently to engage the adjacent slot 8 in the cross-head portion 2 of the upper member. This arrangement facilitates assembling although the pivot pin could extend thru one end of the cross-head members to the other.

In that portion of the cross-head 15 adjacent the opposite and cooperating cross-head 2 with its teeth 7 I provide a corresponding set of teeth 18 which will register and cooperate with the interstices between the teeth 7 with a somewhat loose or sliding fitting action. Thus the spaces between the teeth 7 in the top cross-head 2, as indicated at 17, will receive the teeth 18 in the lower cross-head 15; and the corresponding recesses 19 in the lower cross-head 15 will receive the projecting teeth 7 in the upper cross-head 2. Therefore, any material engaged therebetween will be clamped and crimped together.

It is important to provide a forward sliding action relatively between the lower crimping

cross-head 15 and the upper cross-head 2, the slot 8 being of suitable length for this purpose so that the pivot pins 20 will traverse the same; and for this purpose I unite the handles by a toggle link 25 pivotally secured as indicated at 26 to a pair of lugs 27 welded or otherwise attached in the lower part of the upper handle 1 and the side flanges 3; and to the lower handle 10 the toggle link is pivoted as indicated at 28 to a pair of upstanding lugs 29 secured to the lower handle.

If desired, the lower lugs 29 may be formed integral with the side flanges 12, but in the upper handle 1 I prefer to form the lugs 27 spaced from the side flanges 3 so as to permit the housing action when the handles 1 and 10 are compressed, allowing the side flanges 12-12 to span the lugs 27-27 and, thus, nest between the lugs 27 and the side flanges 3-3, as will be readily understood.

While the link 25 and the length of the slots 8-8 afford a limit of relative longitudinal movement between the handles 1 and 10 and, hence, between the crimping teeth 7 and 18, I may also prefer to provide an adjustable stop for this purpose. Also, I desire to fit a coiled spring 30 between the handles 1 and 10 and combine the same with an adjustable stop 21. This latter would be a threaded bolt passing thru a correspondingly threaded hub 22 and extending thru the top of the handle 1, I provide a bearing for the adjacent part of the coiled spring 30, which latter would have its opposite end fitted around a stud 33 secured to the lower handle 10, as best shown in Fig. 3.

This spring is, preferably, fitted between the toggle 25 and the pivots 20, as shown, and acts to automatically open the handles or spread them apart and retract the crimping teeth in the cross-heads 2 and 15 by the action of the toggle link 25 when pressure on the handles has been released, thus setting the crimping tool ready for the next operation.

In Fig. 5 I have illustrated a typical aluminum or other metal box, having a rectangular body portion comprising sides 40 and ends 41 to which a lid 44 is applied. This lid is, preferably, formed with an upstanding rim around its top edge 45, ending in a downturned flange 46 extending entirely around the cover. The side and end walls 40 and 41 are also preferably provided with a downturned flange 48, see Fig. 6, although this is not essential as the flange 46 can be clamped and crimped by my tool on the upstanding walls of the box.

I secure the advantage of a better sealing action where two flanges are thus in contact and are operated on by the cooperating crimping teeth. With the cover applied, my crimping tool is fitted on either side or end, with the teeth 7 overlapping and engaging the top rim 45 and with the depending flange 46 fitting over the rim of the box or over the rim flange 48 depending from the box. Thereupon, a squeezing action on the handles 1 and 10 forces the cooperating head portions 2 and 15 together and the crimping teeth 7 and 18 into interlocking engagement, squeezing the material of the cover and box together as the toggle link 25 and slot 8 with its

cam surface 9 forces the heads to travel together in a relative impinging relation against the interposed cover and box portions. Thus a sealing and crimping action is quickly and simultaneously effected along the entire edge of the top and box being operated on, giving a tight union as indicated at 50, see Figs. 7 and 8.

My crimping tool may be formed with any desired size, height, shape, or form of interlocking teeth or, indeed, may be formed simply with cooperating rib structures, but I prefer the teeth-crimping action as this is important, particularly where thin metal and aluminum is being operated upon to positively stretch and seal together the materials of the box and cover so operated on. The adjustable stop 21 may be threaded thru the hub 22, if desired, to limit the closing action of the interlocking teeth and thus prevent too great pressure being applied on the material being crimped so as to prevent cracking or breaking the same.

I claim:

A crimping tool of the kind described comprising upper and lower crossheads, each having cooperating teeth extending toward each other, the upper crosshead being of greater length and having a handle extending at right angles thereto formed as a channel with depending sides, the lower crosshead having a handle extending at right angles parallel with the upper handle and adapted to nest therein, the depending sides of the upper handle portion adjacent the crosshead each having slanting cam slots therein, pivot pins extending from the lower crosshead into said slanting cam slots constituting a pivotal connection between the upper and lower crossheads, a link between the handles and pivoted to each handle in an inclined position, movement of the handles together and the action of said link forcing the pivots to traverse the cam paths and press the cooperating teeth in the crossheads into interlocking relation, the length of said cam slot and the relative size of said interlocking teeth preventing actual contact of the teeth with each other, in combination with the spring normally acting to separate the handles and move the crosshead from operative to inoperative position to the limit afforded by said cam slots.

RALPH G. AREY.
